Primary Examiner — Cynthia Ramirez*Assistant Examiner* — Xavier Marti-Santos(74) *Attorney, Agent, or Firm* — Barley Snyder(57) **CLAIM**

The ornamental design for a flag pole mount assembly, as shown and described.

DESCRIPTION

FIG. 1 is a front, top and left side perspective view of a flag pole mount assembly;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a rear, bottom and right side perspective view of the flag pole mount assembly.

The broken lines show portions of the flag pole mount assembly which form no part of the claimed design.
